FASTENING MEANS

Henry Mackey, Dayton, Ohio, assignor of two-thirds to Mary Harnish, Dayton, Ohio

Application July 30, 1936, Serial No. 93,518

1 Claim. (Cl. 189—36)

The invention relates to fastening means designed primarily for use in securing a boiler seam protector of the general type disclosed in U. S. patent to Gage, No. 1,223,781 of April 24, 1917, owned in part by myself, although useable also for other purposes. In the protector shown by the patent, in which anchor blocks are connected with heads of the boiler seam rivets, said anchor blocks often become detached from the rivet heads due to expansion and contraction of the boiler or to burning of the block and head connecting means. Therefore, the seam protectors constructed in accordance with the patent have not been as satisfactory and efficient as they should be but the present invention aims to provide, and in actual practice, has provided, a new and improved structure which more securely connects the anchor blocks to the rivet heads.

With the foregoing in view, the invention resides in the novel subject matter hereinafter described and claimed, description being accomplished by reference to the accompanying drawings.

Fig. 1 is a transverse section through a boiler seam and the protector applied thereto, showing the improved fastening means.

Figs. 2 and 3 are sectional views on lines 2—2 and 3—3 of Fig. 1.

Fig. 4 is a perspective view of one of the anchor blocks.

Fig. 5 is a perspective view of one of the protector attaching members.

Fig. 6 is a perspective view of one of the refractory protector sections.

Fig. 7 is a detail section showing how the anchor blocks may be welded to the boiler if desired.

While the claimed invention is a securing means capable of general application, it has been shown with a boiler seam protector, and the following description will be worded accordingly.

In the drawings above briefly described, 10 45 denotes a riveted seam of boiler plate 11, the rivets 12 being provided with the usual inner and outer heads 13 and 14 respectively. In boilers in which the inner heads 13 are subjected to the fire, the protector is applied over 50 and connected with these heads, but in other boilers in which the outer heads 14 are subjected to the fire, the protector is installed to cover the outer side of the seam and is connected with said heads 14, the latter arrangement being herein disclosed. Some of the adjacent rivet heads are

modified by providing them with minor areas 14^a at an obtuse angle to their major plate-abutting areas 14^b, said minor areas 14^a diverging from the boiler plate 11 and coacting therewith in forming grooves 14^c.

Rectangular anchor blocks 15 are provided for reception between the modified rivet heads of the seam, each of said blocks having a face 15^c to abut the boiler plate 11, said face being wider than the distance between said rivet heads and terminating in feather-edges 17 for snug reception in the grooves 14^c. In forming the feather-edges 17, the opposite side edges 16 of each block 15 are concavely beveled. It is an easy matter to adapt the rivet heads of any boiler for engagement with the feather-edges 17, as the necessary modification of the heads to form the grooves 14^c, may be readily accomplished with a cold chisel, a special diamond-point chisel, or other suitable tool, and after said edges 17 have once been started into said grooves, the block 20 may be readily driven endwise into final position. Not only do the feather edges 17 facilitate connection of the blocks 15 with the rivet heads, but they establish connections between the rivet 25 heads and blocks which will withstand years of service which was not true of the block and head connecting means shown by the patent above mentioned.

Somewhat narrower anchor blocks 15^a may 30 be welded to the boiler wall as shown at 15^b in Fig. 7 should the owner of the boiler not wish to have the seam rivets notched or disturbed in any way.

Channel-shaped protector attaching members 35 18 are shown, the channels 19 of said attaching members receiving the anchor blocks 15 and the rivet heads. These attaching members are secured to the anchor blocks 15 by cap screws 20 passing through openings 21 in said attaching 40 members and threaded into openings 22 in said blocks, the heads of said cap screws being countersunk at 23 in the members 18. These members 18 and the refractory sections 24 of the protector, are relatively shaped to provide a 45 dove-tail connection 25 which securely connects the protector sections 24 with the attaching members 18.

As the channel of the member 19 is preferably V-shape in transverse section, the ends of the 50 anchor blocks 15 may well be beveled as shown at 26 to engage the diverging sides of said channel. Within this channel, the member 18 is preferably provided with a boss 27 to abut the outer side of the block 15.

By providing the novel construction shown and described, the protector may be much more strongly connected with the rivet heads and difficulties encountered with the structure shown in Patent No. 1,223,781 are therefore overcome, enabling the production of an efficient long-lived protector to well protect boiler seams against fire cracks and leaks.

I claim:—

- 10 In a fastening means, a plate, two rivets passing through said plate and having rivet heads spaced apart at one side of said plate, said rivet heads each having a major area tightly abutting

said plate and a minor area diverging from said plate, whereby said minor areas and said plate jointly form two grooves of acute angular cross section, said acute angular grooves being in opposed relation, and an anchor block having an opening into which to thread a member-fastening screw, said anchor block being disposed between said rivet heads and having two feather edges snugly received in said acute angular grooves, said anchor block having an inner face 10 terminating at said feather edges and tightly abutting said plate.

HENRY MACKEY.
